Patented Dec. 24, 1974

233,972

CHILD'S DRINKING MUG AND LID THEREFOR

Sven-Eric Juhlin, Gustavsberg, Sweden, assignor to AB
Gustavsbergs Fabriker, Gustavsberg, Sweden

Filed June 19, 1972, Ser. No. 264,251

Claims priority, application Sweden Dec. 21, 1971

Term of patent 14 years

Int. Cl. D7—01

U.S. Cl. D7—10

FIG. 1 is a top front perspective view of a child's drinking mug and lid therefor showing my new design; FIG. 2 is a top plan view thereof on an enlarged scale; and

FIG. 3 is an exploded perspective view thereof.

The bottom of the mug is plain and unornamented. The side of the design not shown is the same as the side shown.

I claim:

The ornamental design for a child's drinking mug and lid therefor, as shown and described.
